UNITED STATES PATENT OFFICE.

WILLIAM H. SCHOONMAKER, OF MONTCLAIR, NEW JERSEY

STOP MECHANISM.

1,121,138.

Specification of Letters Patent. Patented Dec. 13, 1914.

Application filed September 15, 1910. Serial No. 582,128.

To all whom it may concern:

Be it known that I, WILLIAM H. SCHOONMAKER, of Montclair, Essex county, State of New Jersey, have invented certain new and useful Improvements in Stop Mechanisms, of which the following is a full, clear, and exact specification, such as will enable others skilled in the art to which it appertains to make and use the same.

10 The object of my invention is to provide an automatic stop device particularly applicable to sound reproducing machines, by which the motion of the record and other parts of the machine is arrested at the end 15 of the reproduction of the thing that is recorded.

The invention is intended particularly for use with those machines employing a flat disk record, but it is applicable to other machines as will fully appear hereinafter.

20 Devices with the same object have to my knowledge been patented previous to my invention, but they have involved contacts on the record and reproducer and these are objectionable in that they interfere with the process of manufacture of the records and further in that they are unsightly and cumbersome. My invention seeks to accomplish the end in view without this disadvantage.

25 To this end the invention consists in certain novel features of construction and combination of parts which will be fully set forth hereinafter and particularly pointed out in the claims.

30 Reference is now had to the accompanying drawings which illustrate as an example the preferred embodiments of my invention.

40 In these drawings—

Figure 1 is a perspective view of a disk-type sound reproducing machine showing parts broken away to expose parts of my improved stop motion mechanism. Fig. 2 is a side elevation of the contact arm and its 45 adjusting devices, showing the sound carrying arm of the machine; Fig. 3 is a detail section showing the manner of mounting the contact arm; Fig. 4 is a side elevation 50 of the stop actuating devices; Figs. 5 and 6 are detail views of the circuit breaker and stop applier; Fig. 7 is a diagram of the circuit; and Fig. 8 is a plan view of a disk type machine fitted with a modified form of 55 the stop mechanism.

The type of the machine in Fig. 1 is that

of a disk record, and in said view 10 indicates the box containing the motor; 11 the arm supporting the sound tube 12; 14 the reproducer, and 15 the disk, which is shown 60 broken away to disclose certain parts of my invention.

The sound tube 12 is mounted in an upper bearing 16 on the arm 11 and coincident with the axis of said bearing the tube is provided with a downwardly projected stud 17, which bears on the pin 18 carried by the arm 11, and serving as a stop bearing for the arm allowing it to swing across the face 70 of the record disk as is usual in such machines. To this stud 17 a disk 19 is securely fastened and the disk carries on its edge an annulus 20 which is free to rotate around the disk, said annulus being curved 75 interiorly to receive the disk as shown in Fig. 3. Projecting upward on the annulus 20 is an arm 21 with which a link 22 is articulated and this in turn is articulated to a suitable adjusting device, here shown as a finger lever 23, coacting with a quadrant 24. The annulus 20 also carries a contact arm 25 which is fast on the annulus and projects from the same under the record disk, lying between the same and the top of the box 10. The annulus 20 and its arm 25 are held fast with the tube 12 by means of the devices 21, 22 and 23, and therefore the arm 25 follows the motion of the tube. Said arm, however, may be adjusted relatively to the tube by the lever 23 and its 80 connection.

26 indicates a contact mounted suitably insulated on the top of the box 10, and in the path of the arm 25, and adapted to be engaged thereby when the reproducer 14 85 has reached the end of the record. For this purpose the arm 25 has a contact 27 and upon the engagement of the parts 26 and 27 the electrical circuit forming part of my invention will be closed. Preferably the contact 26 is in the form of a permanent magnet and the contact 27 is of magnetic metal so that the instant contact is made the parts are attracted to each other and held engaged 100 thus preventing vibration of the lever 23 105 and a consequent uncertainty of operation.

The contact 26 is connected by a wire 28 to the circuit breaking device shown in detail in Figs. 5 and 6. This consists of two metal fingers 29 and 30 arranged within the 110 box 10 and insulated from each other by an insulation bracket 31. The finger 30 is

resilient and tends to spring away from the finger 29 as shown in Fig. 5. Said fingers are provided with contacts 32 which when engaged close the circuit but which break 5 the circuit when separated as in Fig. 5.

Mounted vertically in the box is a rock shaft 33, the upper end of which projects above the box and is provided with an eccentric brake 34 adapted to engage the periphery of the table on which the record 15 is mounted. The motion of this brake into active position is controlled by a stop screw 35 carried in a stud 36 on top of the box. By adjusting this screw the extent to which 15 the brake engages the table may be regulated. A torsional spring 37 is coiled around the shaft 33 and serves to throw the brake into operation. The shaft 33 carries at its lower end an arm 38 which, when the brake 20 is not active, is engaged with an insulation extension 39 on the finger 30 and holds said finger in the position shown in Fig. 6 in which the circuit is closed. The parts are retained as in Fig. 6 by a detent 40 on the 25 armature 41 on an electromagnet 42. The armature 41 is held raised by a spring 43 and when the armature is attracted the detent 40 moves down with the armature 41 disengaging the detent 40 from the projection 30 44 on the arm 38. This allows the spring 37 to assert itself and relieves the spring arm 30 breaking the circuit as well as throwing the brake 34 into engagement with the table of the machine stopping the same with that 25 degree of promptness which is permitted by the adjustment of the stop 35.

To relieve the brake it is only necessary to throw it away from the table by manual operation which returns the arm 38, reengaging it with the projection 39 and closing the circuit. Thereupon the parts are held in this set adjustment by reengagement of the elements 40 and 44. The machine is provided with means for manually applying the brake at any time, consisting simply of a push pin 45, which is vertically movable in a bearing 46 in the top of the box 10 and adapted to engage the armature 41. A spring 47 may be provided to hold the push pin raised. By depressing the pin 45 the armature 41 may be moved down releasing the arm 38 the same as though the armature had been attracted by the magnet. The arm 30 is connected by a wire 48 to the electromagnet 42 and this is joined by a wire 49 to a battery 50, which in turn is grounded on the arm 11.

The operation of the apparatus may be traced as follows: The circuit is normally closed at the arms 29 and 30, but is open between the contacts 26 and 27. Upon starting the operation of the machine the tube 12 and the arm 25 begin to travel toward the center of the record and the arm should be 65 adjusted relatively to the tube so that when

the end of the record is reached the contact 27 will engage the contact 26 and be held engaged therewith by the magnetic character of the latter. This closes the circuit. Instantly the armature 41 is attracted the 70 arm 38 is released. Two things then happen, namely, the circuit is broken at the arms 29 and 30 and the spring 37 throws the brake 34 into engagement with the table of the machine stopping the motion thereof. 75 The parts are restored to operative position by manually releasing the brake as explained.

In sound reproducing apparatus of the class in question the records are of varying 80 lengths and therefore it is impracticable to make a permanent adjustment which will stop the machine at proper intervals for the various records. It is therefore necessary to adjust the arm 25 to suit the particular record being produced. In the practical application of my invention therefore it is only necessary to provide a scale on the quadrant 24 or other adjusting device and to mark upon each record a numeral or character 85 corresponding to those on the quadrant. The operator then upon starting the machine need only adjust the lever 23 to the character marked on the record which he is about to use. For example, if a record of 90 a given length is marked with the numeral 3 then the operator turns the lever 23 to the point marked 3 on the quadrant. In other respects the action is wholly automatic.

It should be obvious that by a mere reversal of organization the adjustment referred to may be effected by movement of the contact on the box 10, as distinguished from the movement of the contact which 105 swings with the sound tube. An example of such an arrangement is shown in Fig. 8, where the arm 25^a instead of being adjustably mounted on the sound tube 12 is fastened securely thereto and moves with it as 110 a unit. The contact 26^a is adjustable toward and from the contact 27^a by mounting it on an arm 52 in turn carried by a vertical rock shaft 53 suitable mounted in the box 10 and extending into the same. The 115 contact 26^a therefore swings in an arc toward and from the contact 27^a and to insure engagement at all times the former contact is arc-shaped as shown.

To the rock shaft 53 a link 54 is joined 120 through an arm 55 on the shaft. This link is pivoted to one arm of an elbow lever 56 fulcrumed in the box 10 and having its other arm projected out of the box alongside of a quadrant 57. On this quadrant is 125 a scale of the same character and for the same purpose as the quadrant 24. By adjusting the lever 56 the adjustment of the contact 26^a will follow.

Having thus described my invention what 130

I claim as new and desire to secure by Letters Patent of the United States is:

1. The combination with a rotatable member, and a swinging member arranged to travel across said rotatable member during the rotation thereof, of motion-arresting means for said rotatable member, comprising an arm pivotally-connected to said swinging member to move with respect thereto for purpose of adjustment, a notched sector secured to said swinging member, a swinging lever arranged to move with respect to said sector and provided with means adapted to engage the notches of said sector to secure the lever in different positions with respect to said sector, means connecting said lever to said arm, whereby motion of said lever with respect to said sector effects change of position of said arm with respect to said swinging member, and means arranged to be engaged by said arm at a predetermined point in the movement of said swinging member and by reason of such engagement to effect arrest of said rotatable member.
2. The combination with a rotatable member, and a swinging member arranged to travel across said rotatable member during the rotation thereof, said swinging member provided with a disk, an arm provided with an annulus embracing said disk and supported thereby but movable rotatively with respect thereto, said annulus provided with a projection, adjusting means movably mounted upon said swinging member and connected to said projection, whereby said arm may be moved with respect to said swinging member, said adjusting means comprising means for securing the said arm, with respect to the swinging member, in various adjusted positions, whereby said arm when so secured will move with said swinging member, and means arranged to be engaged by said arm at a predetermined point in the movement of said swinging member and by reason of such engagement to effect arrest of said rotatable member.
3. The combination with a rotatable member, and a member arranged to travel across said rotatable member during the rotation thereof, of two contact pieces, one movable with said traveling member and arranged to contact with the other of said contact pieces, at a predetermined point in the movement of said traveling member, one of said contact pieces being magnetized and the other being of magnetic material, whereby a firm contact between said contact members is assured, and a circuit controlled by said contact members and including means arranged, when operated by said circuit, to effect arrest of said rotatable member.
4. The combination with a rotatable member, a motor for rotating said member, a case inclosing such motor, the said rotatable member being exterior to the case, and a member arranged to travel across said rotatable member during the rotation thereof, of motion arresting means for said rotatable member comprising a brake adapted to engage said rotatable member, means tending to move said brake into engagement with said rotatable member, a detent normally preventing such movement of such brake, an electro-magnet adapted when energized to operate said detent to release said brake, a circuit including said magnet, contact means operated by said traveling member arranged to close said circuit at a predetermined point in the operation of said traveling member, and spring contact means included in said circuit and located within said case and held closed by said detent when the latter is holding back the brake, said detent arranged to release said spring contact means to permit same to open said circuit when the brake is released.

In testimony whereof I have signed my name to this specification in the presence of two subscribing witnesses.

WILLIAM H. SCHOOONMAKER.
